ATTORNEY

UNITED STATES PATENT OFFICE.

THEODORE SCHMIDT, OF DAYTON, OHIO.

PACKAGE-BOX.

SPECIFICATION forming part of Letters Patent No. 292,863, dated February 5, 1884.

Application filed September 15, 1883. (No model.)

To all whom it may concern:

Be it known that I, THEODORE SCHMIDT, a citizen of the United States, residing at Dayton, in the county of Montgomery and State 5 of Ohio, have invented a certain new and useful Improvement in Package-Boxes; and I do hereby declare that the following is a full, clear, and exact description of the invention, which will enable others skilled in the art to 10 to which it appertains to make and use the same, reference being had to the accompanying drawings, and to the letters of reference marked thereon, which form a part of this specification.

15 My invention relates to improvements in paper packing-boxes; and it consists of interlocking the end and side laps on the top of the box, and in such manner that the contents tend to tighten rather than loosen the package. The construction is such that the tucks of one side enter the slots of the opposite, to bind them together, and the tucks of the end laps enter slots in the side laps, to hold the ends of the package in position.

20 The packing-box is illustrated in the accompanying drawings, in which Figure 1 is a view of the blank. Fig. 2 is a top view of the packing-box with one end open.

Like letters designate like parts throughout the several views.

25 A represents a paper blank as it is prepared preparatory to folding and interlocking of the sides and ends, with a view to forming a package-box, the object being to construct out of a

firm paper a box which will securely retain its 35 contents. The paper is creased, as shown by dotted lines at *a a'*, *b b'*, *c c'*, and *d d'*. The lap *E* forms one side and top, the same having end laps, *k*, folded in on the ends, tucks *e² e²*, and slots *g g*. The lap *E'*, forming the other 40 side and top, has longitudinal slots *g' g'* and transverse slots *i i*, and also end laps, *k k*. The end laps, *F F'*, are identical, each having two tucks, *e e'*.

When the paper blank is prepared as illustrated at Fig. 1, the box is formed by turning in the end laps, then bringing the side laps together and putting the tucks *e² e²* into the slots *i i*. Then the end laps are brought over the top and the tucks *e e* and *e' e'* enter slots *g g* 50 and *g' g'* in the side laps, and then the package-box is complete.

Having fully described my invention, what I claim, and desire to secure by Letters Patent, is—

55 A package-box creased for folding, as specified, having side laps, *E*, with tucks *e² e²* and slots *g g*, lap *E'*, with slots *g' g'* and *i i*, and laps *F F'*, with each two tucks, *e e* and *e' e'*, and four end laps, *k*, substantially as set forth. 60

In testimony that I claim the foregoing as my own I affix my signature in presence of two witnesses.

THEODORE SCHMIDT.
